UNITED STATES PATENT OFFICE.

ALEXANDER WINRAM THOMPSON, OF HAGERSVILLE, ONTARIO, ASSIGNOR, BY DIRECT AND MESNE ASSIGNMENTS, OF TWO-THIRDS TO THOMAS T. MARSHALL, OF JARVIS, AND GEORGE A. PHILP, OF ST. THOMAS, CANADA.

CRIMPING-MACHINE.

SPECIFICATION forming part of Letters Patent No. 308,012, dated November 11, 1884.

Application filed March 13, 1884. (No model.)

To all whom it may concern:

Be it known that I, ALEXANDER W. THOMPSON, a subject of the Queen of Great Britain, residing at Hagersville, in the county of Halton, Province of Ontario, Dominion of Canada, have invented certain new and useful Improvements in Machines for Crimping the Uppers of Boots and Shoes, of which the following is a full, clear, and exact description.

10 My invention relates to an improvement in machines for crimping the uppers of boots and shoes.

15 The machine is composed, essentially, of a slotted bed or former and a reciprocating plunger operated by a lever and any suitable power, the leather being forced by the descent of the plunger through the slot in the bed, receiving in the operation its shape from the former.

20 The invention consists in various peculiarities of construction tending to increase the efficiency of the machine, and it is illustrated in the accompanying drawings, in which—

25 Figure 1 is a side elevation of the machine. Fig. 2 is an end elevation. Fig. 3 is a plan. Fig. 4 shows both a side elevation and a plan of the slotted keeper-plate, and Fig. 5 is a sectional view of the plunger.

30 B indicate the frame-work of the machine, made preferably of metal and supported by standards I. The inner side of each frame is recessed for a portion of its length, so that a slot is formed when the side pieces are bolted together, as shown in Fig. 3. On the bolts (four of which are preferably used) and between the face of the side pieces and the nuts E are rubber washers or cushions, which yield sufficiently to permit a slight lateral movement of the side pieces B when the plunger enters the slot.

40 D represents the former, made preferably of metal and of the shape which the leather is to assume. The former is secured within a recess in the upper edges of the frame B, and upon it rests a slotted metallic keeper-plate, 45 C, Fig. 4, which fits the former accurately. The leather is held between the plate C and the former. The dotted lines M show the ex-

tent of the slot in Fig. 1. A bracket, K, is formed with or secured to one of the frame-pieces B, and to this bracket is pivoted the power-lever G. From this lever is suspended by a link, j, the plunger A. The plunger is made of metal of width sufficient to permit it to pass through the slotted former when depressed. Its lower edge is of the same shape as the former. The plunger is connected directly to the bracket K by two parallel rods, H H, pivoted at both ends, respectively, to the plunger and bracket. The movement of these rods tends to carry the plunger forward as it is depressed, causing it to enter the former in a precisely vertical plane. A leaf-spring, L, is attached to the former to secure the edge of the leather.

55 In operating my machine, the leather is secured between the plate C and the former D. The plunger A is then forced through the slot, carrying the leather with it and forming the crimp.

60 Obviously the machine may be operated by hand, or the lever connected in any way to power.

What I claim is—

1. The combination of the longitudinal side pieces recessed on their inner faces intermediate of their ends to form a slot when brought together and constituting a bed-frame, the former secured within a recess in the bed-frame, the slotted keeper fitted to the former, and the hinged plunger, substantially as described.

75 2. The bed-frame composed of yielding side pieces, B, in combination with the former D, plate C, plunger A, and parallel rods H H, substantially as described.

80 3. The combination, with the frame, of the operating-lever G, the suspended plunger, and the pivoted parallel rods H H, substantially as described.

ALEXANDER WINRAM THOMPSON.
